AUTOMATIC CONTROL FOR ELECTRIC SIRENS

Filed July 3, 1926

UNITED STATES PATENT OFFICE

MICHAEL REULE, OF CHARLESTON, ILLINOIS

AUTOMATIC CONTROL FOR ELECTRIC SIRENS

Application filed July 3, 1926. Serial No. 120,479.

This invention relates to improvements in electrical circuit breakers and more particularly to a novel combination and arrangement of a switch for intermittently closing a circuit and a circuit breaker for effecting discontinuance of the operation of the switch after a predetermined cycle of operation, and the invention is directed more especially to the employment of such a combination of circuit controlling devices in connection with a motor driven siren for sounding fire alarms. The general object of the invention is to provide means whereby an alarm mechanism of the class referred to may be set in operation and, in a predetermined cycle of operation, will sound a predetermined number of siren blasts and then cease to function, automatically.

Another object of the invention is to provide a circuit breaker extremely simple in construction and highly efficient in operation, and to so construct the circuit breaker that the same may be adjusted or reset in the event of improper functioning of any of the electrical devices with which it is associated.

In the accompanying drawings:

Figure 1 is a view partly in side elevation and partly in section, illustrating the device embodying the invention.

Figure 2 is a top plan view thereof, the view illustrating also diagrammatically, the circuit in which the various component parts of the device are interposed.

In the drawings, the siren is indicated in general by the numeral 1 and is illustrated only in a general way as is also the electric motor 2 for operating the same, inasmuch as these devices are of the ordinary construction and in themselves do not enter into the present invention, the present invention being concerned solely with the provision of means for controlling the supply of current to the siren motor 2 to effect operation of the siren a predetermined number of times and then effect a discontinuance of the operation, automatically. The means provided for intermittently closing the circuit through the siren motor 2 to intermittently operate the siren comprises an intermittent circuit closer or switch indicated in general by the numeral

3. This switch comprises a shaft 4 which is rotatably mounted at one end in a suitable bearing in a frame 5 and at its other end in a gear case indicated by the numeral 6, and a drum 7 is mounted upon the said shaft and 55 this drum comprises two sections indicated, one by the numeral 8 and the other by the numeral 9, which are bridged and connected together by insulating strips 10, the sections being individually provided with spokes or other devices of insulating material, indicated by the numeral 11, supporting the sections upon the shaft 4. A contact ring 12 is mounted upon the section 8 of the drum and extends circumferentially of one end 60 thereof and is in electrical contact or, in other words, not insulated from this section of the drum, which section is of metal as also the section 9. A similar ring 13 is mounted upon one end of the drum section 9 and directly in contact therewith. The drum also carries, between the rings 12 and 13, a pair of arcuate contacts 14 and 15 which extend approximately two-thirds of the circumference of the drum. A contact brush 16 is 75 mounted upon and insulated from the casing 6 and continuously contacts the ring 12 and a similar brush 17 is secured upon and supported by a bar 18 of insulating material mounted in the frame 5 and engages the contact ring 13. Other contact brushes 19 and 20 are supported by the insulating bar 18 and are respectively positioned to be engaged by the contacts 14 and 15. A conductor wire 21 is connected with the contact brush 16 80 and to one terminal of a three blade double throw switch 22 which controls the supply of current to the motor 2, which motor is of the three phase type. Another conductor wire 23 is connected with the contact brush 17 and engages the contact ring 13. Other contact brushes 19 and 20 are supported by the insulating bar 18 and are respectively positioned to be engaged by the contacts 14 and 15. A conductor wire 21 is connected with the contact brush 16 85 and to one terminal of a three blade double throw switch 22 which controls the supply of current to the motor 2, which motor is of the three phase type. Another conductor wire 23 is connected with the contact brush 17 and engages the contact ring 13. Other contact brushes 19 and 20 are supported by the insulating bar 18 and are respectively positioned to be engaged by the contacts 14 and 15. A conductor wire 21 is connected with the contact brush 16 90 and to one terminal of a three blade double throw switch 22 which controls the supply of current to the motor 2, which motor is of the three phase type. Another conductor wire 23 is connected with the contact brush 17 and engages the contact ring 13. Other contact brushes 19 and 20 are supported by the insulating bar 18 and are respectively positioned to be engaged by the contacts 14 and 15. A conductor wire 21 is connected with the contact brush 16 95 and to one terminal of a three blade double throw switch 22 which controls the supply of current to the motor 2, which motor is of the three phase type. Another conductor wire 23 is connected with the contact brush 17 and engages the contact ring 13. Other contact brushes 19 and 20 are supported by the insulating bar 18 and are respectively positioned to be engaged by the contacts 14 and 15. A conductor wire 21 is connected with the contact brush 16 100 and to one terminal of a three blade double throw switch 22 which controls the supply of current to the motor 2, which motor is of the three phase type. Another conductor wire 23 is connected with the contact brush 17 and engages the contact ring 13. Other contact brushes 19 and 20 are supported by the insulating bar 18 and are respectively positioned to be engaged by the contacts 14 and 15. A gear 30 is fixed upon the end of the shaft

4 which extends into the gear casing 6 and this gear meshes with the worm 31 upon a shaft 32 which is rotatably mounted in the gear casing and extends at one end beyond the gear casing and has fixed thereon a pulley 33. A belt 34 is trained about the pulley and about a pulley 35 which is fixed upon the shaft 36 of a motor 37, preferably mounted upon the base of the frame 5. A conductor wire 38 is led from a source of current supply to one binding post 39 of the motor 37 and another conductor wire 40 is led from the same source of current supply to one terminal or contact of the circuit breaker embodying the invention, which circuit breaker is indicated in general by the numeral 41 and will now be described.

The circuit breaker 41 comprises a stub shaft 42 which is mounted upon the frame 5 and is provided with a reduced portion 43 upon which is rotatably mounted a gear 44 upon the face of which is secured a disc 45 of insulating material which, in turn, has mounted upon its outwardly presented face a contact disc 46 of metal. For a purpose to be presently explained, the contact disc 46 has a segment cut from its peripheral portion to provide a notch or recess 47 exposing a part of the disc 45. The circuit breaker further includes a supporting block 48 of insulating material upon which are mounted two contact brushes, one indicated by the numeral 49 and the other by the numeral 50. The brush 49 bears at its free end against the face of the contact disc 46 at a point so spaced with relation to the center of the disc and the recess 47 as to be at all times in contact with the said disc during the rotation of the disc. The free end of the other contact brush 50, however, engages the face of the disc 46 at a point adjacent the periphery thereof and in the path of travel of the recessed portion 47 of the disc, so that at a period in the rotation of the contact disc, the recess 47 will assume a position opposite the free end of the contact brush 50 and the brush will then be out of contact with the disc 46. A pinion 51 is fixed upon the outer end of the drum shaft 4 and meshes with the gear 44, and the gear 44 and pinion 51 are so proportioned that the gear will be rotated one complete revolution in four complete revolutions of the drum shaft 4, assuming that, as in the present instance, the siren is to be operated to sound four successive blasts.

A conductor wire 52 is connected with the other binding post 53 of the motor and leads to the contact brush 49, and the conductor wire 40 heretofore referred to, is led to the other contact brush 50, a snap switch or any other similar type of simple switch 54 being interposed in the wire 40. A collar 55 is fixed upon the reduced portion 43 of the shaft 42, and a compression spring 56 is fitted onto this portion of the shaft and bears at one end

against the collar and at its other end against the outer face of the gear 44 so that normally the gear 44 is held in position with its hub portion engaging against the shoulder provided by reducing the shaft 42 and is in mesh with the pinion 51. However, should it become necessary to compensate for any overrunning of the drum shaft 4 or any other imperfect operation of the motors or the intermittent circuit closer, the gear 44 may be grasped at its periphery and slid outwardly upon the shaft 42 until disengaged from the pinion 51 and then rotated to a proper position and then returned to position meshing with the pinion 51, through the action of the spring 56.

With the parts substantially in the positions shown in Figures 1 and 2 of the drawings, the apparatus is set in operation by turning the snap switch 54 to close the circuit through the motor 37, the contacts 49 and 50 being at this time bridged by the contact disc 46. The motor will impart rotary motion to the shaft 32 and through the worm 31 and gear 30 to the shaft, and as this shaft is rotated together with the drum 7 carried thereby, the contacts 14 and 15 will be brought into engagement with the contacts 19 and 20 and the circuit will be closed through the motor 2 and kept closed until the said contacts 14 and 15 pass from engagement with the contacts 19 and 20. If it were not for the provision of the circuit breaker embodying the invention, the drum 7 would, of course, continue to rotate so long as the motor 37 was supplied with current, but with the gear 44 and pinion 51 proportioned as above stated, the recess 47 in the disc 46 will, at the end of the fourth revolution of the drum 7, be brought to a position opposite the engaging end of the contact brush 50, and the circuit through the motor 37 will be broken, thus stopping the rotation of the drum 7 and consequently breaking the circuit through the motor 2, the contacts 14 and 15 being at such time clear of the contacts 19 and 20. It will be understood, of course, that the gear 44 and pinion 51 may be variously proportioned so as to provide for rotation of the contact drum 7 any desired predetermined number of times to effect operation of the siren a corresponding number of times.

It will be evident that in the rotation of the drum 7, the circuit will be closed through the motor 2, in the present instance, four times in a complete revolution of the gear 44, and that, as previously stated, by reportioning this gear and the pinion 51, either or both of them, as may be found expedient, any desired number of blasts of the siren may be produced. The pulleys 33 and 35 are, of course, so proportioned, as are also the gear 44 and pinion 51, that at the end of the cycle of rotation of the drum 7, during which cycle the last blast of the siren is sounded, the contact

brushes 19 and 20 will be opposite the spaces between the ends of the respective contacts 14 and 15 and at this time the contact 50 will be out of contact with the disc 46. In order to again sound the siren, the apparatus is set in operation by first rotating the pulley until the contact brushes 19 and 20 are out of contact with the contact members 14 and 15 and the ends of the said members are substantially equi-distantly spaced from their respective contact brushes, whereupon the gear 44 is retracted, as previously stated, against the tension of the spring 56, and rotated until the end of the contact brush 50 contacts the said disc immediately at one end of the arcuate or segmental recess 47, whereupon, upon closing the switch 54, the apparatus will be again set in operation and will operate to automatically give the required number of blasts from the siren.

Having thus described the invention, what I claim is:

The combination with the drum shaft of an intermittent circuit closer, and a motor for operating the said shaft, of a circuit breaker comprising a shaft, a gear rotatable thereon, a pinion upon the drum shaft meshing with the said gear to impart rotary motion thereto, said gear being movable longitudinally of the shaft upon which it is mounted whereby to be shifted into and out of mesh with the pinion, and a spring mounted on the shaft and bearing against the gear for holding the same in position to mesh with the pinion, a contact disc carried by and insulated from the gear and having an interrupted portion, and contacts in circuit with the motor, one of the contacts engaging the disc in the path of movement of the interrupted portion thereof and the other contact engaging the disc at another portion thereof.

In testimony whereof I affix my signature.
MICHAEL REULE. [L. s.]
